UNITED STATES PATENT OFFICE

NORVIN G. MALONEY, JR., OF KEY WEST, FLORIDA

REGENERATIVE ATOMIZING AND VAPORIZING DEVICE

Application filed July 13, 1929, Serial No. 378,162. Renewed January 30, 1931.

This invention relates to atomizers and vaporizers and has as its primary object the provision of a device of the character mentioned for use in connection with internal combustion engines, the function of the device being to combine relatively non-volatile liquid fuels of low viscosity and air into an air-borne saturated vapor of minimum heat contents suitable for internal combustion engines.

Another very important object of the invention is to provide a device of this nature whereby the liquid fuel in a highly atomized state may be intermingled with heated air, the device creating a terrific turbulence of air current, thereby increasing the rate of vaporization to a considerable degree, the said mixture of air, vapor, liquid drops being acted upon by centrifugal force and the fuel intermingled with the air in the form of fog and vapor to be fed to the internal combustion engine in a relatively dry vapor-like state.

Another very important object of the invention is to provide a device of this nature fully capable of obtaining the result above enumerated and which, at the same time, will be inexpensive, simple in construction, can be readily and easily applied to any internal combustion engine, without materially altering the construction of the engine, will be positive and efficient in operation, at all times, and otherwise well adapted for the purpose for which it is designed.

Other objects and advantages of the invention will become apparent during a study of the following description, taken in connection with the accompanying drawings, wherein:

Figure 1 is an end view of my device.

Figure 2 is a vertical longitudinal sectional view therethrough.

Figure 3 is a vertical transverse sectional view, taken substantially on the line 3-3 of Figure 2.

Figure 4 is a vertical transverse sectional view, taken through one of the units or section casing forming a part of the assembled device as shown in Figure 2,

Figure 5 is a fragmentary side elevation of the device.

Figure 6 is a detail sectional view through the manifold of one of the units, showing the diagonal baffle plate located therein.

Figure 7 is a fragmentary detail sectional view, showing the manner of securing the shaft supporting plate within one of the units.

With reference more in detail to the drawings, it will be seen that my improved atomizing and vaporizing device comprises what may be generally designated as a sectional casing, the same being indicated by the reference character 5. As intimated the casing comprises end sections 6 and 7 respectively and intermediate sections 8.

Although I have herein shown but one intermediate casing 8, it is to be understood that any number may be employed according to the desire of the user. All of the sections are substantially circular in configuration and comprise inner and outer spaced peripheral walls 9 and 9' respectively, the end units or casing section 6 being closed by one wall 10, said casing being open on its other side as clearly indicated. This wall 10 providing a front closure for the entire device, while the other end casing 7 is closed on one side thereof through the medium of the wall 11, which wall 11 constitutes a closure for the opposite end of the entire device 5. The wall 10 of the end casing 6 is provided with an intake opening 12, a tubular neck 13 surrounding this opening 12 and extending forwardly of the assembled structure 5, as shown to advantage in Figure 2. At its opposite end, the tubular casing or neck 13 is adapted to be coupled in any suitable manner to the engine, so that air preheated by the exhaust of the engine may be conducted therethrough inwardly of the unit 5.

The intermediate section 8 is closed on one side thereof by a circular wall 14, which wall 14 is provided with a central opening 15, whereby said section 8 may communicate with the end section 6, as will be hereinafter more apparent.

The wall 14 of the section 8 is provided with an inwardly directed peripheral flange

16, which flange is so formed as to provide a shoulder 17, extending about the outer periphery thereof. Thus the flange, at its peripheral edge is reduced as at 18 and this 5 reduced edge of the flange is telescoped in the open side of the end section 6, the shoulder 17 abutting the peripheral edge of said end sections 6 so as to limit the inward movement of the flange 16 within said end section 10 6 and at the same time permitting of a tight joint connection between said end section and intermediate section 8 as shown to advantage in Figure 2.

The other end section 7 is also provided 15 on its opposite side with a circular wall 19 in every respect similar to the wall 14 of the intermediate section 8, the said wall 19 being provided with the peripheral flange 20 shou- 20 dered as at 21 and having its reduced edge 22 receivable in a telescopic manner within the open side of the intermediate section 8 as also clearly illustrated in Figure 2. This wall 19 is also provided with a central opening 23 in alignment with the openings 12 25 and 15 respectively, thus affording communication of the end section 7 with the intermediate section 8 so that the preheated incoming air may pass entirely through the assembled sections to exhaust through the 30 centrally disposed outlet opening 24 formed in the wall 11 of the end section 7. A tubular neck or passage 25 surrounds this opening 24, leading therefrom to be coupled in any suitable manner with the intake manifold of 35 an internal combustion engine.

The inner walls 9 of all of said units are provided on their inner faces with spiral ribs 26, the ribs forming therebetween liquid fuel receiving and conducting passages 27. 40 These ribs or fins as they may be designated are designed like threads in a nut and coil around the respective units so as to lead toward the outlet 24 of the assembled section. This is also clearly shown in Figures 45 2 and 4. The purpose of these ribs and their passages 24 formed therefrom will also be hereinafter more fully explained.

Circular baffle plates or discs 28 are vertically disposed within the intermediate section 8 and the end section 7 concentrically 50 with respect to their peripheral flanges 18 and 20 respectively. These plates are suitably supported through the medium of suitable brackets 29 extending from the walls 14 and 55 19 respectively, the said plates being secured to the outer ends of these brackets as at 30. A third plate 31, similar in every respect to the first mentioned plates 28 is supported concentrically within the end casing section 7, 60 through the medium of suitable brackets 32, similar to the brackets 29, which brackets 32 extend outwardly from the inner face of the wall 11 of said end section 7, being dis- 65 posed thereon in circumferentially spaced relation about the outlet opening 24, said plate

31 being secured to the ends of these brackets as at 33. Each of said plates 28 and 31 respectively is provided with a centrally disposed opening 34, and a shaft 35, extends horizontally through the assembled sections and is rotatably supported in the openings of the said plates as shown to advantage in Figure 2. Hubs 36 are keyed in any suitable manner upon the shaft 35, said hubs being arranged on that portion of the shaft extending 75 through the respective sections. Fan blades 37 extend radially from the respective hubs 36, the hubs 36 and the blades 37 being positioned on the shaft forwardly of the plates 28 and 31 respectively for rotation within the 80 respective sections between one wall of the section and one of the plates 28. Of course, the fan 28 within the end section 7 will be disposed therein between the plate 31 and the wall 19, the fan in the intermediate section being positioned between its walls 14 and that plate 28 supported on the wall 19 of the end sections 7, while lastly that fan 85 rotatable within the end section 6 will be disposed therein between the wall 10 of the section and the plate 28 supported on the wall 14 of the intermediate section 8.

A tubular liquid fuel conduit line 32, leading from a suitable source of supply, communicates with the inner end of the intake 95 passage 13 with an opening 33, formed at said end of the intake passage 13. Any suitable means (not shown) may be utilized for rotating the shaft 25, consequently imparting rotation to the fan blade 37, whereby the 100 heated air entering the assembled sections through the intake 12 will be forced through the assembled sections consequently from one section to another in a turbulent manner, the liquid fuel from the conduits 32 intermin- 105 gling with said air and of course being carried through the section to exhaust with the air through the exhaust opening 24 from there to be conducted in an air-borne saturated vapor state to the engine, supplying 110 the fuel to the engine. In this connection, it will be noted that the spinning blade, whose main purpose is to create a powerful turbulence of air currents or eddies will result in somewhat of a boiling action, and at the same 115 time, causing a complete mixing of fuel vapors and air.

The sections are of course held in assembled relation through the medium of suitable bolts or other connecting members 34, 120 extending through the aligned apertures of radially disposed ears 35, which ears or lugs 35 are formed on the adjacent or abutting edges of the respective sections as shown to advantage in Figure 2.

The inner and outer walls of the respective sections form therebetween manifolds 36, the manifolds of the respective sections communicating with one another when said sections are in assembled relation to provide a con- 125

tinuous manifold circumjacent the entire assembled unit 5, as is apparent from a study of Figure 2. A diagonal baffle plate 37 is spirally disposed within each of the manifolds 36 of the respective sections, the baffle plates permitting of but one revolution of the exhaust around each section, it being understood that the manifold 36 in the end sections 6 and 7 respectively are provided with inlet and outlet ports 38 and 39 respectively, the inlet port 38 having suitable communication with the exhaust of the internal combustion engine so that some of the exhaust gases may be utilized for heating the inner wall 8 of the respective sections, the exhaust gases entering the manifold 36 in the end sections 7 being guided by means of the baffle plate 37 within the manifold of that end section 7 around said section to exhaust therefrom where the manifold 36 of said end section 7 communicates with the manifold of the intermediate section 8 such as at 39. The exhaust gases having made one revolution about and within the manifold 38 of the intermediate section 8, the gases are then expelled into the manifold 36 of the end section 6, where the manifold of said intermediate sections 8 and said end section 6 communicated such as is designated as at 40, after which the exhaust gases pass through the outlet or exhaust opening 39 of the exhaust manifold of the end section 6 as is apparent.

Thus the fuel and the heated air within the respective sections being agitated by the blade of the fan within the respective sections, the blade will cause all of the drops which are not air-borne (fog) of fuel to be thrown out by centrifugal force against the inner surfaces of the inner walls 27 of the respective sections, which walls 27 are heated through the medium of the exhaust gases as just explained. Of course, some of the liquid fuel will accumulate within the graved passages 27 formed on the inner face of the inner walls of the respective sections and if this liquid is not carried up to the crest of the ridges and atomized, the blast of air set up by the fan will cause the oil to circulate through these passages 27 in the direction of rotation of the blade, the blades carrying the liquid back toward the intake end of the next adjacent section, where the liquid is forced through a plurality of conduits or openings 41, formed in the flanges 18 and 20 of the plates 14 and 19 respectively, it being obvious that adjacent these plates 14 and 19 the pressure is increased, since due to the centrifugal force the pressure in any advance unit is greater than in the preceding unit.

These holes 41 are small so that the amount of air flowing back is negligible, consequently there is practically a continuous movement of the air and fuel in one direction through the assembled sections, namely in that direction leading toward the exhaust

opening 24. It may be well to mention that the holes 41 in the respective plates 14 and 19 are numerous, each hole draining several of the graved passages 27. The invention also contemplates the provision of an overflow or scavenger outlet 42 for the oil, this outlet 42 being common to all of the sections. The outlet 42 is formed preferably in the lower end portion of the wall 10 of the end section 6, the outlet being disposed a little above the passages 27, so as to allow the liquid to accumulate in a pool in the section 6, the level of the pool, of course, being always maintained so as not to permit the liquid coming in contact with the outer edges of the blades 37. This drain outlet 42 is in communication with a passage 43, which passage 43 communicates at its upper end as at 44, with the air intake passage 13, with the result that the suction of the air stream will carry the atomized or vaporized fuel back into the unit or assembled casing 5, while the heavy liquid oil will drain off.

From the foregoing then, it will be seen that a vaporizer of this nature will prevent fuel in a liquid state other than fog from getting through to the engine, since the centrifugal force set up within the assembled casing section will throw all drops which are not actually floating in air to the heated inner wall of the respective sections, where it will either be re-atomized or run around between the ribs or fins 26 to the back of the sectional casing and through the small holes 41 to the preceding section. A further advantage of this device is that lower temperatures may be used due to the fact that all of the liquid fuel is almost constantly in contact with the heated walls of the respective sections, the additional heat that would be required to penetrate a stratum of air being consequently unnecessary thereby reducing the volumetric expansion of the mixture to a minimum. A further advantage of a device of this nature is that the extreme turbulence of air caused by the revolving blades not only increases the rate of vaporization but also thoroughly mixes the air and fuel vapors, this terrific mechanical convection tends to keep throughout the units an even temperature.

It will be also apparent from the foregoing description that a device of this nature may be manufactured at a relatively small cost, can be readily and easily applied to any internal combustion engine, and that the same will be positive and efficient in operation and well adapted to the purpose for which it is designed. Even though I have herein shown and described the preferred embodiment of my invention it is to be understood that the same can be used to advantage with many devices other than with internal combustion engines and is suscep-

tible to changes fully comprehended by the spirit of the invention as herein described and the scope of the appended claims.

What is claimed is:

5. 1. In an atomizing and vaporizing device of the class described, a casing having oppositely disposed, inlet and outlet ports, said casing comprising end sections and intermediate sections, means for forcing heated air 10 into said casing, a shaft rotatably supported in said casing, a plurality of fans secured to said shaft for rotation therewith, there being one fan within each of said sections, each of said sections being of substantially 15 circular formation, each of said sections having inner and outer spaced peripheral walls, means for passing heated gases between said walls, means for forcing liquid into said casing, said sections having liquid receiving 20 passages formed therein on the inner faces of the inner walls of the respective sections, said passages extending spirally about said sections in a direction corresponding to the direction of rotation of said fans, and liquid 25 conduits between the respective sections and communicating with said liquid passages as and for the purpose specified.

2. In an atomizing and vaporizing device for internal combustion engines, a casing 30 comprising a plurality of sections, means for forcing heated air through the sections of the casing prior to the entrance of the air into the internal combustion engine, means for forcing liquid fuel into the sections of 35 the casing prior to its entrance into an internal combustion engine, means for causing a turbulent passage of the mixed air and fuel through said casing prior to the entrance of the mixture into the internal combustion engine, each of said sections of said casing comprising inner and outer peripheral walls, means for forcing heated exhaust gases 40 of the engine between said inner and outer walls, the inner wall of the respective sections having spiral ribs formed thereon, said ribs being spiralled in a direction corresponding to the direction of flow of the mixed fuel and air through the sections of the casing, and oil ducts communicating with the 45 ribs in the respective sections to provide a passage for the liquid accumulating between said ribs for directing the oil from one section to the preceding section, as and for the purpose specified.

53. 3. In an atomizing and vaporizing device for internal combustion engines, a casing, said casing comprising end sections and an intermediate section, means for securing said sections in intercommunicating relation, each 58 of said sections comprising an inner and outer spaced peripheral wall, means for supplying exhaust gases between said peripheral wall, means for forcing heated air to the respective sections, means for forcing liquid fuel to 63 the respective sections, to mingle with said

air prior to the entrance of the mixture into the internal combustion engine, liquid fuel receiving passages spirally formed on the inner face of the inner walls of the respective sections, liquid fuel ducts between the 70 respective sections communicating with the liquid fuel passages formed in said sections, apertured faces supported within said casing at the connected ends of said sections, a shaft extending through the apertures in the plate 75 for rotation within said section, a plurality of fans supported on said shaft adapted for rotation with said shafts, there being one fan arranged within each of said sections for agitating the mixture of liquid fuel and 80 heated gas for forcing said mixture turbulent- 85 ly from one section to the other in successive relation, a baffle plate arranged between the walls of each of said sections, the baffle plates of the respective sections cooperating to pro- 90 vide a circuitous passage for the exhaust gases from one section to the next succeeding section.

4. An atomizing and vaporizing device 95 for internal combustion engines comprising a casing having an inlet and an outlet, means for forcing air into said casing through the inlet, a fuel feed pipe communicating with the inlet for feeding fuel to the air prior to the entrance of the air into said casing, spaced walls concentrically arranged in said 100 casing, fans arranged in the casing in alternate relation with respect to the walls, said walls having central openings formed therein, the central openings being in alignment with the inlet and outlet of said casing, and circumferentially spaced vapor passages formed in the respective walls inwardly from the periphery of the walls, and means for heating the casing.

5. An atomizing and vaporizing device 105 for internal combustion engines comprising a casing having an inlet and an outlet, means for forcing air into said casing through the inlet, a fuel feed pipe communicating with the inlet for feeding fuel to the air prior to the entrance of the air into said casing, spaced walls concentrically arranged in said 110 casing, fans arranged in the casing in alternate relation with respect to the walls, said walls having central openings formed therein, the central openings being in alignment with the inlet and outlet of said casing, and circumferentially spaced vapor passages 115 formed in the respective walls inwardly from the periphery of the walls, and means for heating the casing, said casing further comprising inner and outer spaced peripheral walls, to provide an exhaust gas passage 120 concentrically with the casing, having an inlet at one end of the casing, and an exhaust at the opposite end of the casing, and liquid fuel conducting passages spirally formed on the inner face of the inner peripheral wall of 125

the casing, for conveying liquid fuel to said circumferentially spaced vapor passages.

6. An atomizing and vaporizing device for internal combustion engines comprising a casing having an inlet and an outlet, means for forcing air into said casing through the inlet, a fuel feed pipe communicating with the inlet for feeding fuel to the air prior to the entrance of the air into said casing, spaced walls concentrically arranged in said casing, fans arranged in the casing in alternate relation with respect to the walls, said walls having central openings formed therein, the central openings being in alignment with the inlet and outlet of said casing, and circumferentially spaced vapor passages formed in the respective walls inwardly from the periphery of the walls, and means for heating the casing, said casing further comprising inner and outer spaced peripheral walls, to provide an exhaust gas passage concentrically with the casing, having an inlet at one end of the casing, and an exhaust at the opposite end of the casing, and liquid fuel conducting passages spirally formed on the inner face of the inner peripheral wall of the casing, for conveying liquid fuel to said circumferentially spaced vapor passages, concentrically arranged baffle plates in the casing interposed between the fans and said concentric walls, and means for directing the exhaust gases through said exhaust passage in a circuitous manner from the inlet to the exhaust of said passage.

35 In testimony whereof I affix my signature.
